UNITED STATES PATENT OFFICE.

DANIEL L. WILCOX, OF PAWTUCKET RHODE ISLAND.

DESIGN FOR GAME-BOARD.

SPECIFICATION forming part of Design No. 12,259, dated May 10, 1881.

Application filed September 23, 1880. Term of patent 7 years.

To all whom it may concern:

Be it known that I, DANIEL L. WILCOX, of Pawtucket, in the county of Providence and State of Rhode Island, have invented and produced a new and original Design for Game-Boards, of which the following is a full, clear, and exact description, reference being had to the accompanying drawing, forming part of this specification.

10. The drawing is a perspective view of my newly-designed game-board.

My design consists in a shield-shaped game-board having a curved base extended into a projection having a handle thereon, and having chamfered edges, as shown in the accompanying drawing.

In the drawing, *a* is the game-board, the out-

line of which resembles a heraldic shield, and having a curved base which is extended out at its center, and has a handle, *c*, thereon, as 20 shown. This handle may be either plain, as shown in full lines, or of fanciful form, as shown in broken lines. The edges *d* of the shield are chamfered, as shown. The face of the board has a number of holes formed therein to receive removable pins *b*.

What I claim is—

The design for a game-board herein shown and described.

DANIEL L. WILCOX.
